Geo. P. Kimmel.
ATTORNEY.

UNITED STATES PATENT OFFICE.

WESTER KETOLA, OF JERSEY CITY, NEW JERSEY.

PAPER CLIP.

Application filed March 25, 1922. Serial No. 546,819.

To all whom it may concern:

Be it known that I, WESTER KETOLA, a citizen of the Republic of Finland, residing at Jersey City, in the county of Hudson and State of New Jersey, have invented certain new and useful Improvements in Paper Clips, of which the following is a specification.

This invention relates to paper holding 10 clip devices, and has for one of its objects to provide a device of this character of improved utility and increased efficiency.

Another object of the invention is to provide a device of this character which may be 15 constructed wholly of metal, and of any required size and strength of "grip."

With these and other objects in view the invention consists in certain novel features of construction as hereinafter shown and described and then specifically pointed out in 20 the claims, and in the drawings illustrative of the preferred embodiment of the invention:—

The figure represents the improved device, partly broken away to illustrate the 25 interior construction of a portion of the device.

The improved device includes a support or base, preferably of two portions 10 and 30 11 at right angles to each other, and of wood or metal as may be preferred.

Mounted on the portion 10 of the support, is a combined holding plate 12 and housing 35 13, the latter tubular transversely and with circular ends, one of which is represented at 14, and with guideways at the ends, one of which is represented at 15, next to the circular ends. Disposed within the tubular portion 13 is a centering rod 16 bearing at 40 its ends against the inner faces of the circular portions 14.

The improved device includes a spring controlled gripping portion including a member formed of a section of relatively 45 heavy resilient wire bent substantially into U shape to produce spaced sides 17 and a transverse connecting portion, the latter bent into coils one of which is represented at 18 and encircling the rod 16 with the portion 50 of the transverse connecting portion between the coils bent laterally as shown at 19 and bearing on the adjacent portion 10 of the support.

The flat portion 12 of the housing bears 55 over the lateral projection or loop 19 and thus holds the coils in position.

Supported on the sides 17 of the gripping portion is a plate 20 secured to the portions 17 by rolling the edges of the plate around the same as shown at 21.

Formed in the plate 20 are a plurality of elongated U shaped clefts whereby holding lips 22 may be bent up from the plate to provide means for supporting a memorandum tablet 23.

At its free edge the plate 20 is provided with spaced clefts to release a portion adapted to be bent outwardly into a finger grip 24, to facilitate the releasing of the gripping member.

The bearing portion of the improved device is preferably formed of a single section of wire bent to the required shape and including side loops 25 and 26, a continuous transverse portion 27, and a divided transverse portion 28 and 29.

The transverse portions 28 and 29 are upturned at their confronting ends, as indicated at 30, and the edges of the plate 23 at the sides of the lip portion 24 are rolled 80 around the transverse portions 28 and 29, the upturned portions 30 preventing the lateral displacement of the bearing member.

The spring coil 18 operates to hold the bearing member yieldably against the portion 11 of the support, as will be obvious.

The improved device is simple in construction, may be manufactured of any required size or capacity, of any suitable material, and may be employed wherever a yieldable 90 clip is required to hold papers or like articles.

The preferred embodiment of the invention is disclosed in the drawings and set forth in the specification, but it will be understood that modifications within the scope 95 of the claimed invention may be made in the construction without departing from the principle of the invention or sacrificing any of its advantages.

Having thus described the invention what is claimed as new is:—

1. A clip device comprising a support, a resilient wire bent substantially into U shape to produce spaced sides and a connecting 105 portion, said connecting portion turned into coils, a housing on said support and enclosing said coils and holding them from rotation relative to the support, a plate member attached to the side portions of said U shaped 110 member, and a bearing member swinging on the plate.

2. A clip device comprising a support, a resilient wire bent substantially into **U** shape to produce spaced sides and a connecting portion, said connecting portion turned into 5 coils, means for holding said coils from rotation relative to the support, a plate member attached to the side portions of said **U** shaped member, a bearing member formed of wire and including transverse portions, and means for swingingly connecting said plate to said transverse portions.

In testimony whereof, I affix my signature hereto.

WESTER KETOLA.
